UNITED STATES PATENT OFFICE.

SERN P. WATT, OF MORGAN PARK, ILLINOIS, ASSIGNOR TO HINE-WATT MANUFACTURING COMPANY, OF CHICAGO, ILLINOIS, A CORPORATION OF ILLINOIS.

DOOR-CHECK.

SPECIFICATION forming part of Letters Patent No. 711,686, dated October 21, 1902.

Application filed January 2, 1902. Serial No. 88,103. (No model.)

To all whom it may concern:

Be it known that I, SERN P. WATT, residing at Morgan Park, Cook county, Illinois, have invented certain new and useful Improvements in Door-Checks, of which the following is a specification.

My invention relates to a door-check of the same general construction and operation as that described and claimed in my prior application, filed August 27, 1901, Serial No. 73,475, and is intended as an improvement upon the door-check device shown in said application.

The object of the present invention is to simplify the construction and increase the efficiency of my door-check, making the same in every way most reliable, easy of repair and assembling, and already having the proper adjustment and regulation.

In the accompanying drawings, Figure 1 is a vertical section of my door-check; Fig. 2, a horizontal section thereof on line 2 of Fig. 1; Fig. 3, a perspective of a portion of the flange on one of the disks, showing the means for holding or anchoring the outer end of the coiled spring; and Fig. 4 a section of the tubular extension or bearing-sleeve on the casing, showing the groove for holding the inner end of such coiled spring.

The casing 1, which is of suitable type and dimensions, has a chamber in which the working parts of the door-check proper operate. The actuating shaft or spindle comprises a stem 2 of two parallel disks 3 and 4, which are almost of the same cross-sectional area as said chamber, so that there is no frictional engagement metal to metal at the sides, the lower disk 4 resting upon the substantially flat bottom or floor of the chamber. There are thus formed two chambers 5 and 6, the upper chamber being adapted to hold oil, grease, or other suitable lubricant, and hence here called the "oil-chamber," and the lower chamber being adapted to hold the checking fluid, preferably a mixture of alcohol and glycerin, and hence here called the "check-chamber." The upper disk 3 is provided with a vertical marginal flange 7, forming a cylinder fitting closely but operatively in the upper portion of the casing and constituting the

walls of the oil-chamber, such cylinder in the present instance extending substantially to the top of the casing. As shown, the disks and flange 7 are provided with suitable packing 8 to prevent the possibility of the liquid used in the check-chamber from being forced up from the pressure thereof and between the inner wall of the casing-chamber and the outer surface of the cylinder. The casing is here shown closed at its top and adapted to be closed at the bottom by a screw-cap 9. A tubular extension or sleeve 10 depends centrally from the top of such casing down as far as the disk 3, thereby providing an accurate and long bearing for the operating shaft or spindle 2. Suitable packing 11 and packing-nut 12 may be employed. The shaft 2 has a central bore in which extends and screws the regulating-valve 13, whose lower end 14 is preferably made conical and constitutes the valve proper. This valve is adapted to control or restrict communication between the two radial passages 15 and 16 in the said spindle, which passages correspond to the similar passages in the device described in my said former application and which communicate between the high and low pressure chambers on the opposite sides of the movable abutment. The movable abutment 17, its fastening-pin 18, and its check-valved passage 19 being similar to the corresponding parts in my said former application will require no detailed explanation or illustration. The inner wall of the cylinder or shell 7 is provided with vertical opposite recesses 20 and 21, (more clearly shown in Fig. 3,) which are adapted to receive and hold or anchor the outer end of the coiled spring 22. The two recesses are provided so that the spring may be reversed. The tubular extension 10 is provided with the longitudinal grooves 23 to receive and hold the inner end of such spring. By preference the valve-stem 13 does not extend to the top of the shaft 2, but has a screw-driver slot at its end, so that it may be adjusted up or down, a cap-screw 24 normally closing the end of the shaft. The object of this arrangement is to prevent or hinder change of adjustment by ignorant or inexperienced users, my door-check being adapted

to be properly adjusted at the shop for the work to be done. Furthermore, the amount of spring tension is determined at the shop, the adjustment being obtained by giving the 5 shaft 2 a quarter-turn when the parts are being assembled.

The lower end of the operating-cylinder is bored to form a cylinder or chamber 25, which is closed at its lower end by a screw-plug 26. 10 A piston 27, having a hollow stem 28, operates in said cylinder and is normally downwardly pressed by a spring 29. The upper end of the piston-stem is formed as a valve-seat adapted to fit the valve 14 when such 15 stem 28 is upwardly moved, as hereinafter described. In the event of any too-violent starting or closing of the door from any cause whatsoever the great pressure suddenly created in passages 15 and 16 is communicated downwardly through the hollow stem 28 and below the piston, which is thereupon forced upwardly and its valve-seat brought into contact with the valve, whereby communication between passages 15 and 16 is closed and free 20 movement of the door provided until the great pressure ceases, whereupon the spring 29 will restore the parts to normal position. The object of the plug 26 is to separate the chamber 25 from the check-chamber, so that the pressure 25 above described in passing through the piston-stem cannot get below the lower disk 4 and tend to raise it and bind the working parts.

The door-check above described is not only 30 simple in construction and operation, but it is so made as to avoid or overcome many of the objectionable features to which devices of this character have been found subject in practical use. My device is therefore not only 35 simple and inexpensive in construction and operation, as just stated, but is reliable and efficient in operation.

The two chambers 5 and 6 are sealed against each other, and the lower chamber 6 is especially sealed in such manner that the alcohol cannot escape or evaporate. Furthermore, the oil or grease in the upper chamber thoroughly lubricates the shaft 2 along its tubular bearing-sleeve 10. All frictional contact 40 between the disks and flange and the sides of the casing is avoided, and consequently there is no binding of such parts. The packing on the disks and flange prevents intercommunication between chambers 5 and 6, and if any 45 greater pressure in the lower chamber should by chance force any of the checking fluid upwardly past the first packing further passage of such fluid would be prevented by the other packings above, so that the two chambers are 50 effectively sealed one from the other. In like manner the movable abutment may have a packing-strip 30 and the stationary abutment 31 one or more strips 32 on its top and bottom.

55 As is well known, suitable checking fluid is highly evaporative, requiring packing and packing-boxes, which do not satisfactorily

prevent evaporation. In my check device, however, the oil or grease in the upper chamber serves the purpose of sealing the check-chamber below, and thereby prevents evaporation of its fluid, as well as the purpose of lubricating the operating-shaft or trunnion. 70

I claim—

1. A door-check comprising a casing having a chamber, an operating shaft or spindle therein provided with two parallel disks bearing in such chamber, one of said disks having an upwardly-extending marginal flange and 80 a fixed and a movable abutment arranged between said disks and a regulated by-pass between opposite sides of the movable abutment. 85

2. A door-check comprising a casing, an operating shaft or spindle therein provided with two parallel disks, one of said disks having a marginal flange, a fixed and a movable abutment arranged between said disks, a regulated by-pass between opposite sides of the 90 movable abutment, said casing having a tubular extension or bearing-sleeve for the spindle. 95

3. A door-check comprising a casing having a chamber, an operating shaft or spindle therein provided with two parallel disks bearing in such chamber, one of said disks having a marginal flange, a fixed and a movable abutment arranged between said disks, a regulated by-pass between opposite sides of the 100 movable abutment, such casing having a tubular extension receiving said spindle, a spring in said chamber and means on both the flange and tubular extension to hold the two ends of the spring. 105

4. A door-check comprising a casing having an integral top portion and open at its lower end, a removable closure for closing such open end of the casing, a central bearing-sleeve forming a part of said top of the casing and depending therefrom, an operating shaft or 110 spindle bearing in said sleeve and door-check mechanism operated by such shaft or spindle. 115

5. A door-check comprising a casing having a chamber into which depends a central tubular extension or bearing-sleeve integral with 120 said casing, an operating shaft or spindle bearing in said sleeve and door-check mechanism operated by such shaft or spindle. 125

6. A door-check comprising a casing having a fluid-chamber provided with a fixed and a 130 movable abutment, an operating shaft or spindle arranged therein, and connected to the movable abutment said shaft having a longitudinal bore connecting with a transverse passage communicating on either side 135 of the movable abutment, a valve in said bore for regulating said passage, and a piston adapted to be moved by extraordinary pressure exerted in said chamber and having a stem movable in the bore and adapted to seat 140 upon the end of said valve to close such passage. 145

7. A door-check comprising a casing having a fluid-chamber provided with a fixed and a

movable abutment, an operating shaft or spindle arranged therein, and connected to the movable abutment, said shaft having a longitudinal bore connecting with a transverse passage communicating on either side of the movable abutment, a valve in said bore for regulating said passage, a stem movable in the bore and adapted to seat upon the end of said valve, and means for automatically actuating said stem under extraordinary conditions and thereby causing restriction of said passage independently of the valve as to its normal function.

8. A door-check comprising a casing having a fluid-chamber provided with a fixed and a movable abutment, an operating shaft or spindle arranged therein, and connected to the movable abutment, said shaft having a longitudinal bore connecting with a transverse passage communicating on either side of the movable abutment, a valve in said bore for regulating said passage, said valve having a substantially conical-shaped end to form the valve proper, a stem having a conical-shaped socket forming a valve-seat for said valve, and means for actuating said stem under extraordinary conditions.

9. A door-check comprising a casing having a fluid-chamber provided with a fixed and movable abutment, an operating shaft or spindle arranged therein, and connected to the movable abutment, said shaft having a longitudinal bore connecting with a transverse passage communicating on either side of the movable abutment, a valve in said bore for regulating said passage, said valve having a substantially conical-shaped end to form the valve proper, a stem having a conical-shaped socket forming a valve-seat for said valve, and having a central bore and a piston connected to said stem.

10. A door-check comprising a casing having a fluid-chamber provided with a fixed and movable abutment, an operating shaft or spindle arranged therein and connected to the movable abutment, said shaft having a longitudinal bore connecting with a transverse passage communicating on either side of the movable abutment, a valve in said bore for regulating said passage, the lower end of said spindle being counterbored to form a cylinder, means for closing the lower end of such cylinder, a piston having a hollow stem which is movable in said bore of the spindle and is adapted to seat against said valve.

11. A door-check comprising a casing having a fluid-chamber provided with a fixed and movable abutment, an operating shaft or spindle arranged therein, and connected to the movable abutment, said shaft having a longitudinal bore connecting with a transverse passage communicating on either side

of the movable abutment, a valve in said bore for regulating the passage said spindle having a piston-chamber 25, closed by a plug 26, a piston 27 adapted to operate in said chamber and having a hollow stem 28 whose free end is formed as a valve-seat.

12. A door-check comprising a casing 1, having a chamber, an operating shaft or spindle 2 having the two disks 3 and 4, the latter thereof bearing upon the bottom of said chamber and the former thereof having an extended marginal flange 7, said casing having a tubular extension or sleeve 10 receiving the spindle, a spring 22 secured respectively to the flange 7 and extension 10, fixed and movable abutments between the disks and means for regulating the equalization of pressure on opposite sides of the movable abutment.

13. A door-check comprising a casing 1, having a chamber, an operating shaft or spindle 2 having the two disks 3 and 4, the latter thereof bearing upon the bottom of said chamber and the former thereof having an extended marginal flange 7, the disks being provided with packing, said spindle having passages 15 and 16 communicating with the space below said disk 3, a valve 14 in said bore for controlling fluid through passages 15 and 16, fixed and movable abutments between said disks, and a spring 22 operatively connected to the casing and to the flange 7.

14. A door-check comprising a casing 1, having a chamber, an operating shaft or spindle 2 having the two disks 3 and 4, the latter thereof bearing upon the bottom of said chamber and the former thereof having an extended marginal flange 7, said flange and said disks being free of frictional contact with the sides of the chamber and having packing.

15. A door-check comprising a casing 1, a shaft or spindle working therein and having two disks whereby there are formed an oil-chamber 5 and check-fluid chamber 6, a movable abutment connected to the disks and a stationary abutment to the casing, and packing arranged on both abutments and on the edges of said disks.

16. In a door-check, the combination of a casing having a checking-fluid chamber and a sealing-fluid chamber, the fluid in the latter chamber serving to seal the first-named chamber and thereby prevent evaporation of its fluid.

17. In a door-check, the combination of a casing provided with door-check mechanism and having a checking-fluid chamber and a second chamber adapted to contain oil which serves to seal the checking-fluid chamber and also to lubricate the door-check mechanism.
